LOCOMOTIVE

Raymond G. F. Loewy, New York, N. Y., and Harold A. Nonemaker, Narberth, Pa., assignors to The Pennsylvania Railroad Company, Philadelphia, Pa., a corporation of Pennsylvania

Application July 17, 1936, Serial No. 91,152

8 Claims. (Cl. 105—2)

This invention relates to steam locomotives and more particularly to the exterior surface configuration of the front end, and the general conformation of the exposed surfaces of the boiler, 5 cab and tender.

One object of the invention is to minimize the resistance occasioned by the passage of the locomotive through the atmosphere and especially to lessen the resistance offered when the locomotive is traveling at high speeds.

Another object of the invention is to improve the vision of the engineman by preventing smoke and cinders issuing from the stack from descending and occupying areas along the sides of the 15 boiler in advance of the forward cab windows.

Another object of the invention is to provide a front end construction substantially free of sharp angles and projecting fittings, and adapted to deflect objects struck by the locomotive in such manner that they are cast clear of the track, avoiding the difficulties which arise when objects are impaled or carried for some distance 20 along the track.

Another object of the invention is to provide an exterior casing which may be readily applied to a conventional type of steam locomotive to convert the same to a locomotive embodying the present invention.

Still other objects and advantages of the invention will become more fully apparent from the description hereinafter set forth of one embodiment or example of the invention, having reference to the accompanying drawings.

Of the drawings:

Fig. I represents a side elevation of a steam locomotive embodying the invention.

Fig. II represents a perspective view of the same;

Fig. III represents a front view of the same; and

Fig. IV is a partial plan view according to the scale of Fig. I, showing the top of the casing surrounding the smoke stack with associated vanes.

The features of construction characteristic of the present invention may be applied to old locomotives by covering the structure with an exterior casing, or in the case of the building of a new locomotive the parts may be originally constructed with the exterior surface characteristics shown and described herein.

With reference to the particular embodiment illustrated in the drawings, the boiler is comprehensively designated at 1, the cab at 2, and the tender at 3. It will be noted that the general contour lines of the locomotive are continued throughout the cab and tender, and that the top

surface is unobstructed by projecting parts or the like and extends continuously in a substantially horizontal plane from one end of the locomotive to the other. Moreover, at the sides the exterior surfaces are likewise smooth and substantially continuous throughout the entire locomotive. At its front end the boiler 1 is provided with a nose 4 which is substantially hemispherical in exterior contour. Desirably a headlight 5 is housed 5 interiorly at the center of the round nose 4. Beneath the round nose 4 there is provided a relatively wide sweeping skirt 6 smoothly rounded and merging with side panels 7. The skirt 6 preferably extends rearwardly at each side a sufficient distance to cover the cylinders, and is so formed 10 that it presents a smooth surface which is adapted to deflect any object struck by the locomotive to one side of the track, and thus eliminate the possibility of the object being impaled and carried along the track. In accordance with safety 15 requirements, a foot board 8 is secured across the skirt, and projects a short distance beyond the front surface thereof in a horizontal plane. The foot board 8 may have perforations distributed 20 thereover so as not to interfere with the flow of air along the outer surface of the skirt 6. The skirt 6 is also provided with a V-shaped furrow 9 which leads from the center line rearwardly 25 and outwardly towards the sides of the boiler 1, thus tending to separate the currents of air impinging on the skirt and to guide such currents 30 in their travel rearwardly along the sides of the locomotive.

At each side of the boiler 1, beneath the level of the forward cab windows 10, a running board 35 11 is provided. The running boards 11 extend horizontally from the forward end of the cab and terminate near the front end of the boiler 1 where they merge with inclined surfaces 12 which lead downwardly toward the skirt 6. The side panels 7 extend in vertical planes from positions outside and near the top of the running gear to the running boards 11, and they form 40 smooth flat sides merging with the rounded surfaces of the skirt 6 and the side walls of the cab 45 2. The running boards 11 have a width corresponding to that of the wings of the cab, and the engineman and fireman have a clear view of the track through the cab windows 10 and along the sides of the boiler 1.

In the areas above the running boards 11, the boiler 1 is of substantially cylindrical shape without projections or exterior fittings which would obstruct the view. At a level above the forward cab windows 10 the boiler 1 is provided at the 50 55

sides thereof with shoulders 14, the side surfaces of which merge with smooth curves with the sides of the boiler. Superimposed upon the boiler 1 is a casing 15 which envelopes the stack and other fittings normally provided at the top of a steam locomotive. It may be assumed that the stack and other fittings are disposed in the usual position at the top of the boiler 1 and are constructed in the customary manner, and that the casing 15 envelopes all of said fittings, except for the top of the stack which terminates at the level of the top of the casing. The top of the smoke stack is flush with the upper surface of the casing 15 through which the smoke stack projects. The casing 15 is rounded at the front as indicated at 16, and has a flat top surface at approximately the level of the cab roof. From the top of the casing 15 vanes 17 in the form of a flat plate project horizontally at each side. The vanes 17, together with the shoulders 14 and casing 15, form ducts or recesses 17a at each side of the stack which serve to conduct currents of air rearwardly over the top of the locomotive. Desirably the plane of the vanes 17 forms a slight angle with the plane of the top surface of the shoulders 15, thereby causing the ducts to converge rearwardly toward the roof 19 of the cab. Moreover, the shoulders 14 are inclined upwardly and rearwardly in such manner that their top surfaces merge with the top surface 18 of the boiler at a point near the forward end of the cab roof 19. The forward wing walls 21 of the cab 2 are inclined outwardly and rearwardly, whereby currents of air traveling rearwardly along the sides of the boiler 1 are displaced outwardly at the cab without sharp deflection. Desirably the side walls of the cab 2 are each provided with a toe board 22 and step 23 formed by grooves or recesses, thus eliminating projecting ledges.

A diaphragm 24, which may be of resilient material, connects the forward end of the tender 3 with the cab 2. As most clearly illustrated in Fig. II, the side walls of the tender 3 are curved to conform generally to the cross-sectional shape of the cab 2 and are of such height that the top surfaces of the tender are continuous and at a common level with the top surfaces 18 of the boiler and the roof 19 of the cab. Marker lights 25 and numeral lights 26 are conveniently housed within the forward ends of the shoulders 14 at the top of the boiler 1.

As shown by the arrows in the drawings, the front end construction of the locomotive is such that the air currents impinging thereon are not sharply deflected, but are caused to adhere to the exterior surfaces and to follow closely along the sides of the boiler 1 and along the side panels 7 in their passage rearwardly along the locomotive. In this manner, irrespective of the direction of the wind, streams of air wash out the areas at each side of the boiler 1 above the running boards 11 in advance of the cab window 10. Moreover, additional columns of air are caused to be conducted through the ducts formed above the shoulders 14, and such currents have a tendency to billow and to travel with relatively high velocity towards the cab roof 19. By reason of the angular convergence of the plane of the vanes 17 with the top surfaces of the shoulders 14, such billowing currents travel rearwardly with increasing velocity, and they create an area of relatively high pressure beneath the stream of smoke issuing from the stack. This counteracts any tendency for the smoke to descend and obscure the

front cab windows 10. The running boards 11 obviate downward drafts of air at the boiler sides which might deflect downward the air currents from the recesses 17a. Under the front nose 4, which overhangs the rearward sloping upper portion of the skirt 6, the upward air flow over the skirt divides, passing upward and rearward over and along the running boards 11 to the sloping front cab walls or wing walls 21. These air currents along the running boards 11 definitely obviate any tendencies toward reduced pressure at the sides of the boiler, which might otherwise result in the downward deflection of the rearward air currents from the recesses 17a. Moreover, it is found that when cross winds are encountered the construction of the front end and the provision of the vanes 17 cause the air currents to follow around the front end of the lee side of the locomotive, rather than to be sharply deflected away from the front end. This has the particular advantage that under cross winds the low pressures ordinarily encountered at the lee side of the locomotive are avoided, and hence the stream of smoke issuing from the stack does not tend to descend towards these areas. Further advantage is gained by the provision of the casing 15 which envelopes all of the conventional fittings, at the top of the locomotive, including the smoke stack. Such projections at the top of a locomotive cause eddying of air currents impinging thereon, and in addition to offering resistance to high speeds, render it impossible to obtain uniform pressures at the top of the locomotive, so as to prevent the smoke from descending in the surrounding regions.

It will be particularly observed that the locomotive of this invention is so designed that the air currents impinging upon the front end travel rearwardly and in substantially parallel horizontal strata along smooth uninterrupted surfaces, adhering closely to the sides and top of the locomotive, including the cab and tender, and washing out the spaces in advance of the cab windows 10, as well as the spaces above the shoulders 14, and such conditions are obtained irrespective of the direction of the wind.

Inasmuch as the movement of the locomotive through the atmosphere does not of itself create wind, but merely displaces the existing air currents of the atmosphere through which the train passes, the avoidance of low pressure areas with consequent descent of the smoke stream is best accomplished by a surface configuration which causes a minimum disturbance of the displaced air, or a mere parting of the wind without sharp deflection or the formation of eddy currents. The structure of the present invention differs radically from many previous attempts at improving locomotive design in that it serves to displace the atmosphere gradually and smoothly, without appreciable turbulence, and with a minimum of disturbance of the normal uniformity of pressure of the atmosphere.

While we have described the invention with reference to one specific embodiment thereof in a steam locomotive, it will be readily apparent that various departures may be had from the specific proportions and shapes described and illustrated herein, and that certain features of the invention may be used to advantage without a corresponding use of other features, all without departing from the spirit of the invention as defined in the annexed claims.

Having thus described our invention, we claim:

1. In a locomotive, a cab, a boiler extending

- forwardly of said cab and formed at its front end with laterally extending shoulders at each side thereof, said shoulders extending longitudinally toward the upper part of said cab, a smoke stack 5 on the forward end of said boiler, a casing of substantial longitudinal extent superimposed on the front end of said boiler above said shoulders and surrounding the sides of said smoke stack, said casing being narrower in width than the 10 width between said shoulders, and vanes projecting horizontally from the top of said casing, said vanes extending laterally over said shoulders and being of a substantial longitudinal extent, the ducts formed by the combination of said vanes, 15 said casing and said shoulders extending rearwardly to conduct over said cab air currents formed in said ducts by the forward motion of said locomotive.
2. The invention of claim 1 wherein said casing 20 has a substantially flat top surface merging with the top of the boiler and the roof of the cab adjacent to the forward portion thereof to form a substantially continuous and flat top surface along the top of the locomotive.
3. The invention of claim 1 characterized by 25 the fact that said boiler has a substantially hemispherical nose, and said casing has a rounded front end and substantially parallel sides.
4. The invention of claim 1 characterized further by the fact that said vanes and said shoulders converge rearwardly toward the roof of 30 said cab.
5. In a locomotive, a boiler, a cab with front windows beside said boiler, a smoke stack on the 35 front end of said boiler, longitudinally extending recesses formed on each side in the upper portion of said boiler below the top of said smoke stack, and having upper and lower defining surfaces, said recesses being open at both ends thereof and formed to receive air at their forward ends below the top of said stack and the smoke issuing therefrom, and being directed rearward toward but above the front cab windows, whereby air currents through said recesses resulting from the forward motion of the locomotive are directed above said windows.
6. The invention of claim 5 wherein said recesses taper rearwardly in vertical width, so as 10 to operate as nozzles in discharging the air currents rearward at high velocities.
7. The invention of claim 5 wherein the recesses are directed rearward above the top of the boiler 15 and the cab roof.
8. The invention of claim 5 wherein running boards are provided along the sides of the boiler below the level of the front cab windows, with downward sloping ends at the front of the boiler, and the front cab walls at each side of the boiler 20 containing said windows are inclined rearward, while the boiler has an overhanging hemispherical nose at its front end, with a subjacent rounded skirt whose surface slopes upward and rearward at either side of said nose substantially to 25 the downward sloping forward ends of said running boards, whereby, owing to forward motion of the locomotive, there is an air flow upward over said skirt, dividing under said overhanging nose, passing upward and rearward over said running boards, and gently deflected by said front cab walls, whereby any tendencies toward reduced pressure at the sides of the boiler and consequent downward deflection of the rearward air currents 30 from the aforesaid recesses are obviated.
